CLAIM

The ornamental design for a cassette carrying case, as shown and described.

DESCRIPTION

FIG. 1 is a front elevational view of a cassette carrying case showing my new design with the cover open;

FIG. 2 is the side elevational view;

FIG. 3 is a rear elevational view;

FIG. 4 is a bottom plan view;

FIG. 5 is an enlarged top plan view taken along line 5—5 of FIG. 1;

FIG. 6 is a partial sectional view taken along line 6—6 of FIG. 5; and

FIG. 7 is a partial sectional view taken along line 7—7 of FIG. 6.

The broken line showing of the interior members in FIGS. 5, 6 and 7 is for illustrative purposes only and forms no part of the claimed design.
